US0D1062564S

(12) **United States Design Patent** (10) **Patent No.:** **US D1,062,564 S**
(45) **Date of Patent:** **** Feb. 18, 2025**

(54) **VEHICLE HOOD**

(71) Applicant: **Oshkosh Defense, LLC**, Oshkosh, WI (US)

(72) Inventors: **Jesse Gander**, Oshkosh, WI (US); **Devon Palmer**, Oshkosh, WI (US); **McCall Groen**, Oshkosh, WI (US)

(73) Assignee: **Oshkosh Defense, LLC**, Oshkosh, WI (US)

(**) Term: **15 Years**

(21) Appl. No.: **29/857,190**

(22) Filed: **Oct. 20, 2022**

Related U.S. Application Data

(60) Continuation of application No. 29/802,921, filed on Aug. 9, 2021, which is a continuation of application No. 29/754,504, filed on Oct. 12, 2020, now Pat. No. Des. 928,672, which is a continuation of application No. 29/700,665, filed on Aug. 5, 2019, now Pat. No. Des. 902,096, which is a continuation of application No. 29/672,849, filed on Dec. 10, 2018, now Pat. No. Des. 860,887, which is a division of application No. 29/602,277, filed on Apr. 28, 2017, now Pat. No. Des. 837,702.
